UNITED STATES PATENT OFFICE.

HOWARD M. DUDLEY, OF PHILADELPHIA, PENNSYLVANIA.

DYEING-MACHINE.

1,280,189.

Specification of Letters Patent.

Patented Oct. 1, 1918.

Application filed September 24, 1917. Serial No. 192,898.

To all whom it may concern:

Be it known that I, HOWARD M. DUDLEY, a citizen of the United States, and a resident of Philadelphia, in the county of Philadelphia and State of Pennsylvania, have invented certain new and useful Improvements in Dyeing-Machines, of which the following is a specification.

My invention refers to dyeing machines and refers particularly to a machine suitable for the dyeing of worsted tops and warp balls.

One object of my invention is a device whereby worsted tops, warp balls and similar fibers may be thoroughly and evenly dyed and treated with liquids.

Another object of my invention is a device whereby fibers in the condition stated above may be dyed and treated without injury to the fiber.

Another object of my invention is a device whereby fibers in the condition stated above may be readily and rapidly packed into dyeing chambers and compressed into a form suitable for even penetration.

Another object of my invention is a device whereby a considerable number of balls, tops, etc., may be dyed equally.

Another object of my invention is a device whereby the condition of the fiber during the dyeing operation may be determined without interrupting the dyeing operation.

Another object of my invention is a testing device combined with the dyeing device in such a manner that the contents of the testing device may be examined without interrupting the operation in the dyeing device.

These and other objects of my invention will be evident upon a consideration of my specification and claims.

The dyeing of worsted tops, warp balls and similar fibers presents several difficulties which must be overcome in order to produce even and satisfactory results.

On account of the physical condition of the fibers they must not be disturbed during the dyeing operation, but must be retained in their original condition. It is further essential that even and uniform penetration of the dye liquid be accomplished in all parts of the fiber mass and it is advantageous that

a means be employed for determining the dyed condition of the fiber without disturbing the fiber or breaking the threads thereof.

The device of my invention overcomes all of these difficulties and presents a method whereby fibers of the character mentioned may be dyed evenly and uniformly and their condition disclosed at any time during the dyeing operation without disturbing the fiber or interrupting the dyeing operation.

The device of my invention consists broadly in a machine in which the tops or balls may be properly compressed within fiber chambers and supported from the openings in the foraminous plates through which the liquid is forced by means which will allow the liquid to be impinged upon practically the entire outer surface of the fiber mass, such flow of liquid being capable of being reversed through the fiber mass. In order to further cause a uniform impregnation of the fiber mass, I insert a converging member in the path of the liquid in such a manner that the liquid will be forced under a uniform pressure and in equal amounts through all of the fiber chambers within the device.

It also embraces a testing machine for determining the condition of the fiber at any time without the expenditure of time and serious effect upon the fiber incident to opening the fiber chambers and removing a portion of the fiber for examination.

The accompanying drawings, in which similar parts are designated by similar numerals, illustrate one form of the device of my invention:

Figure 1 is a side-plan view, partly in cross-section.

Fig. 2 is a cross-section through the line 2—2 of Fig. 1.

Fig. 3 is a cross-section through the line 3—3 of Fig. 1.

Fig. 4 is a broken top-plan view of a foraminous plate of a fiber chamber.

Fig. 5 is a view in the direction of the arrow 5 of Fig. 4.

Fig. 6 is a cross-section through the line 6—6 of Fig. 4.

Fig. 7 is an enlarged cross-section of the testing device.

Fig. 8 is a modification of the bottom portion of the device.

Fig. 9 is a side view of a modified form of a bar in the foraminous plate.

Fig. 10 is an end view of the bar shown in Fig. 9.

In the particular form of a device of my invention, shown in the accompanying drawings, a receptacle 10 has within it a series 10 of cylindrical fiber chambers, 11, 11, 11. The central portion 85 of the receptacle 10 is extended oppositely into the conical members 12, 12. Integral with the sides of the receptacle 10 is an annular angular flange

15 member 13 having the outwardly extended annular member 14. The top 15 is extended outwardly into the pipe 16 which is threaded to the pipe 17. The pipe 17 is connected to the pipe 18 by means of the coupling 19.

20 The pipe 18 carries the valve 20. The lower portion of the top 15 is extended into the annular flange 21. Integral with the top 15 is a series of downwardly extended annular members 24, 24, each of which is slideable within one of the fiber chambers 11, 11 and capable of abutment upon the movable foraminous plates 25, 25. The flange member 21 is movable with respect to the flange member 14 by means of the screw bolts 26.

25 30 35 The pipe 18 carries the valve 20. The lower portion of the top 15 is extended into the annular flange 21. Integral with the top 15 is a series of downwardly extended annular members 24, 24, each of which is slideable within one of the fiber chambers 11, 11 and capable of abutment upon the movable foraminous plates 25, 25. The flange member 21 is movable with respect to the flange member 14 by means of the screw bolts 26 which are threaded therethrough. Integral with the top 15 is a series of concentric plates 22, 22 supported by the cross-bars 23, 23. Integral with the sides of the chamber 10 is angular annular member 28, having the outwardly extended annular member 29. The bottom 30 is extended outwardly into the pipe 31 which is threaded to the pipe 32. The upper portion of the bottom 30 is extended into the annular flange

ception of valves 51, 42, 46, 65 and 67 and the pump started, drawing the liquid from the dissolving tank through the pipes 50, 41, 32 and 31 into the bottom 30 and thence between the nested members 22, 22, the space 105, the plates 35, 35, the fiber mass, the plates 25, 25 and the pipe 45 into the reserve tank 47. When sufficient liquid has been introduced, the valve 51 is closed and the valve 49 opened, thus allowing a continuous circulation of the liquid upwardly through the device. During this operation, the liquid also passes from the space 105 through the conduit 68, the testing device and the conduit 66 into the space 106. From time to time the direction of the liquid stream is reversed by closing all of the valves with the exception of valves 20, 43, 49, 65 and 67, which causes the liquid to flow downwardly through both devices into the reserve tank and to the pump 38.

In order to determine the condition of the treated fiber, the valves 65 and 67 are closed, the testing device removed and the fiber therein examined, the examination being conducted without interrupting the operation in the larger device. When the dyeing operation is completed, the pump 38 is stopped and valve 55 opened, thus draining the liquid from the device. The valve 55 is then closed and the fiber washed by forcing water through the device by means of the pump 38. The device is then opened and the fiber removed.

35 I do not limit myself to the size, number, shape or arrangement of parts as described and shown, all of which can be varied without going beyond the scope of my invention as described and claimed.

40 What I claim is:—

1. In a dyeing machine, in combination, a receptacle, a series of fiber chambers having imperforate sides within the receptacle, each chamber having a fixed foraminous bottom plate and a foraminous top plate 45 slideable within the chamber, means for moving the top plate with respect to the bottom plate and retaining it in any predetermined position, means for passing a liquid in opposite directions through the foraminous plates and the fiber chambers and inwardly diverging members within the path of the liquid adapted to produce a divergence of the liquid column.

55 2. In a dyeing machine, in combination, a receptacle, a series of fiber chambers having imperforate sides within the receptacle, a foraminous bottom plate in each fiber chamber, a foraminous top plate slidably movable within each fiber chamber, means for moving the top plate with respect to the bottom plate and maintaining it in any predetermined position, a series of inwardly diverging members below the bottom plates

adapted to produce a divergence of the liquid column, a series of inwardly diverging members above the top plates adapted to produce a divergence of the liquid column and means for forcing a liquid in either direction through the device. 65

3. In a dyeing machine, in combination, a receptacle, a series of fiber chambers having imperforate sides within the receptacle, a foraminous bottom plate in each fiber chamber, a foraminous top plate slidably movable within each fiber chamber, means for moving the top plate with respect to the bottom plate and maintaining it in any predetermined position, a removable top cover to the receptacle, a series of inwardly diverging members within the top adapted to produce a divergence of the liquid column, a series of inwardly diverging members within the bottom of the receptacle below the fiber chambers, adapted to produce a divergence of 70 the liquid column, a pump, liquid carrying means connecting the top cover with the pump, and liquid carrying means connecting the bottom of the receptacle with the pump to allow of the continuous circulation 75 of a liquid in either direction through the device. 80

4. In a dyeing machine, in combination, a receptacle, a series of fiber chambers having imperforate sides within the receptacle, 90 each chamber having a fixed foraminous bottom plate and a foraminous top plate slideable within the chamber, means for moving the top plate with respect to the bottom plate and retaining it in any predetermined 95 position, oppositely extended convergent members situated centrally of the series of fiber chambers extending above and below the upper and lower plates adapted to produce a divergence of the liquid column, a series of inwardly diverging members situated around the oppositely extended convergent members adapted to produce a divergence of the liquid column, and means 100 for passing a liquid in opposite directions 105 through the foraminous plates and the fiber chambers. 110

5. In a dyeing machine, in combination, a receptacle, a series of fiber chambers having imperforate sides within the receptacle, 115 a foraminous bottom plate having upwardly extended members in each fiber chamber, a foraminous top plate having downwardly extended members in each fiber chamber, means for moving one foraminous plate with respect to the other and maintaining it in any predetermined position, means at each end of the device capable of distributing a liquid evenly over the outer 120 faces of the plates and means for forcing a liquid in either direction through the device. 125

6. In a dyeing machine, in combination, a

- receptacle, a series of fiber chambers having imperforate sides within the receptacle, a foraminous bottom plate having upwardly extended members in each fiber chamber, a 5 foraminous top plate having downwardly extended members in each fiber chamber, means for moving one foraminous plate with respect to the other and maintaining it in any predetermined position, oppositely extended 10 convergent members situated centrally of the series of fiber chambers extending above and below the upper and lower plates adapted to produce a divergence of the liquid column, a removable top to the 15 receptacle, a series of inwardly divergent members within the top adapted to produce a divergence of the liquid column, a series of inwardly divergent members within the bottom of the device adapted to produce a divergence 20 of the liquid column, a pump, liquid carrying means connecting the top of the receptacle with the pump, and liquid carrying means connecting the bottom of the receptacle with the pump to allow of the 25 continuous circulation of a liquid through the device in either direction.
7. In a dyeing machine, in combination, a receptacle, a series of fiber chambers having imperforate sides within the receptacle, a 30 foraminous bottom plate in each fiber chamber, a foraminous top plate slidably movable within each fiber chamber, means for moving the top plate with respect to the bottom plate and maintaining it in any predetermined 35 position, a series of inwardly divergent conduits below the bottom plates, a series of inwardly divergent conduits above the top plates, a removable top cover to the receptacle, a pump, liquid carrying means 40 connecting the top cover with the pump, and liquid carrying means connecting the bottom of the receptacle with the pump to allow of the continuous circulation of a liquid in either direction through the device.
- 45 8. In a dyeing machine, in combination, a receptacle, a series of fiber chambers having imperforate sides within the receptacle, each chamber having a fixed foraminous bottom plate and a foraminous top plate slidable 50 within the chamber, means for moving the top plate with respect to the bottom plate and retaining it in any predetermined position, inwardly diverging members above the top plate adapted to produce a divergence 55 of the liquid column, inwardly diverging members below the bottom plate adapted to produce a divergence of the liquid column, a smaller testing device similar and proportionate to the fiber chambers and exterior 60 to the receptacle, liquid carrying means connecting the portion of the larger device below the bottom plate with the lower portion of the testing device, liquid carrying means connecting the portion of the larger

device above the top plate with the upper portion of the testing device, means whereby the flow of liquid through the testing device may be interrupted without interrupting the flow of the liquid through the larger device and means for forcing a liquid in either direction through the fiber chambers and the testing device.

9. In a dyeing machine, in combination, a receptacle, a series of fiber chambers having imperforate sides within the receptacle, a 75 foraminous bottom plate having upwardly extended members in each fiber chamber, a foraminous top plate having downwardly extended members in each fiber chamber, means for moving one foraminous plate with respect to the other and maintaining it in any predetermined position, inwardly diverging members above the top plate adapted to produce a divergence of the liquid column, inwardly diverging members below the bottom plate adapted to produce a divergence 80 of the liquid column, a smaller testing device similar and proportionate to the fiber chambers and exterior to the receptacle, liquid carrying means connecting the portion of the larger device below the bottom plate with the lower portion of the testing device, liquid carrying means connecting the portion of the larger device above the top plate with the upper portion of the testing device, means whereby the flow of liquid through the testing device may be interrupted without interrupting the flow of the liquid through the larger device and means for forcing a liquid in either direction 85 through the fiber chambers and the testing device.

10. In a dyeing machine, in combination, 95

a receptacle, a series of fiber chambers having imperforate sides within the receptacle, a foraminous bottom plate in each fiber chamber, a foraminous top plate slidably movable within each fiber chamber, means for moving the top plate with respect to the bottom plate and maintaining it in any predetermined position, inwardly diverging liquid distributing means below the bottom plates, inwardly diverging liquid distributing means above the top plates, oppositely extended convergent members situated centrally of the series of fiber chambers extending above and below the upper and lower plates adapted to produce a divergence of the liquid column, a removable top cover to the receptacle, a pump, liquid carrying means connecting the top cover with the pump and liquid carrying means connecting the bottom of the receptacle with the pump, a series of smaller testing devices similar and proportionate to the fiber chambers and exterior of the receptacle, liquid carrying means connecting the portion of the larger device below the bottom plate with the lower 100

portion of each testing device, liquid carrying means connecting the portion of the larger device above the top plate with the upper portion of each testing device, means whereby the flow of liquid through each testing device may be interrupted without interrupting the flow of the liquid through

the larger device and means for forcing a liquid in either direction through the fiber chambers and the testing devices.

Signed at Philadelphia, in the county of Philadelphia and State of Pennsylvania, this 18th day of September, 1917.

HOWARD M. DUDLEY.
